BY Victor J. Evans

ATTORNEY

Levittages,

WITNESS:

UNITED STATES PATENT OFFICE

EDWARD E. PARKER, OF PITTSBURGH, PENNSYLVANIA

WAGON

Application filed December 22, 1930. Serial No. 504,166.

This invention relates to certain new and useful improvements in vehicles and more particularly to the manually operated toy types.

One of the principal objects of the invention consists in the provision and arrangement of a propulsion apparatus of this character within convenient reach of the operator.

An additional object of the invention contemplates the provision and arrangement of a steering mechanism for the vehicle designed to retard undue swaying of the vehicle whereby the occupant thereof will remain seated while turning sharp curves and the like.

With the above and other objects in view, the invention further consists of the following novel features and details of construction, to be hereinafter more fully described, illustrated in the accompanying drawings and pointed out in the appended claim.

In the drawings:

Figure 1 is a longitudinal sectional view taken through the present invention.

Figure 2 is a sectional view taken on line 2—2 of Figure 1.

Figure 3 is a front elevation of the present invention.

Figure 4 is a horizontal sectional view taken on line 4—4 of Figure 2.

Figure 5 is a detail sectional view taken on line 5—5 of Figure 1.

Referring to the drawings in detail wherein like characters of reference denote corresponding parts, the reference character 10 indicates generally a platform upon which a saddle or seat, such as indicated at 11, is arranged. A bolt member 12, carried by the seat member, is adjustably positioned within a slot 13 in the platform 10 whereby the device may be regulated to accommodate operators of different stature.

Supporting plates 14, having attaching ears 15 upon their uppermost ends and secured to the under side of the platform 10, project outwardly and downwardly therefrom to provide spaced parallel apertured ears 16 journally accommodating the immediate portions of a driven axle 17. Traction wheels 18 are fixed upon the outermost ends of the driven axle by key and slot connections, threads or other

well known means of fixation. A brace member 19, having connection at its ends with the supporting plates 14, carries an apertured lug 20 for journally accommodating an appropriate portion of a drive or power transmitting shaft 21. Beveled gears 22 and 23 respectively carried upon the adjacent ends of the drive shaft 21 and the axle 17 are meshingly engaged in rightangularly disposed relation. The drive shaft is extended upwardly at an inclination from the aforementioned drive connection and projected through an appropriate portion of the platform 10 in advance of the slot 13. A lug 24, carried upon the upper side of the platform 10, journally accommodates an appropriate portion of the drive shaft 21 to dispose same in the position shown in Figure 1 of the drawings.

A bracket member 25, of substantially inverted U-shape formation, terminates to provide laterally and outwardly projecting attaching flanges 26 upon the ends thereof secured to the upper side of the platform 10 above the latter mentioned journaled end of the drive shaft. A crank shaft 27, journaled within the opposed sides of the bracket member 25, carries a worm gear 28 thereon meshingly engaged with a complementary gear 29 similarly mounted upon the uppermost projecting end of the drive shaft 21. Crank handles 30, formed upon the outermost projecting ends of the crank shaft 27, are extended therefrom in diametrically opposed relation after the manner of the pedal arms of a bicycle sprocket.

The steering mechanism, alluded to in the foregoing, comprises upper and lower disk members 31 and 32 respectively. The disk 31 is provided with an annular depending flange 33 upon the peripheral edge thereof overhanging the marginal edge of the lowermost disk 32 whereby the latter will be received within the cup of the uppermost disk, substantially as illustrated in Figures 1 and 5 of the drawings. A yoke-shaped hanger 34, of inverted U-shape formation, has its uppermost portion rigidly secured, as at 35, to the under side of the disk 32. The disk 31 is, in turn, rigidly positioned upon the under side of the platform 10 and a pivot pin 36

common to both disks is passed centrally therethrough. An axle 37, carried between the ends of the yoke member 34, has wheels 38 journaled upon the ends thereof. Ears or stops 39, carried by and depending from the annular flange 33 of the disk 31, are located in the path of movement of the depending arms of the said member to restrict undue turning of the steering wheels in either direction. It will be noted that the operator rests his feet upon the axle 37.

The particular arrangement of the disks will obviate undue tilting of the vehicle when turning curves and the like and yet permit the steering mechanism to be operated with excessive ease.

Although I have shown and described the foregoing construction applied to a toy vehicle, it is obviously understood that same could be equally and effectually as well applied upon other forms of vehicles, machines or the like without departing from the spirit of the invention.

Although I have shown and described the invention having the shaft and gearing connections as the means of power transmission, it is obviously apparent that chain and sprocket drives, belt and pulley drives and rope and spindle drives may be employed without departing from the spirit of the invention.

The invention is susceptible of various changes in its form, proportions and minor details of construction and the right is herein reserved to make such changes as properly fall within the scope of the appended claim.

Having described the invention, what is claimed is:

A vehicle comprising a platform having steering wheels, a support for the steering wheels having a disk, a cup-shaped member carried by the platform accommodating said disk for oscillatory shifting motion therein, a pivot connection established between the cup-shaped member and disk, and stops carried by the cup-shaped member disposed in the path of movement of the steering mechanism to obviate undue shifting of the latter when the vehicle veers from its course.

In testimony whereof I affix my signature.
EDWARD E. PARKER.
